INVENTOR

BY *Victor J. Evans*

ATTORNEY

UNITED STATES PATENT OFFICE

BROWN NEAL, OF WICHITA, KANSAS

GARMENT HANGER SUPPORT

Application filed January 20, 1930. Serial No. 422,131. Filed under Act of June 25, 1912, in the Patent Office.

The object of this invention is the provision of a support for garment hangers which may be swung to an out-of-the-way position when garments are supported thereon and which will be effectively latched when swung to such position or when swung to another position to permit of the arrangement of the clothes hangers thereon or the removal of the clothes hangers therefrom.

A further object is the provision of a device for this purpose that includes a wall plate having its ends formed with ears, the upper ear having its end formed with an upstanding flange which is centrally notched, together with a spring wire that includes a lower arm which is crimped and an upper angle arm, the arms exerting a tension toward each other and the ends of the arms being bent to provide pintles which are received through bearing openings in the ears, the pintle on the upper arm having an angle extension to underlie the upper ear, whereby, when the member is swung outwardly on the wall plate the upper arm will be received in the notches of the flange on the upper ear and when swung right angularly with respect to the wall plate the upper arm will be arranged to the rear of and in contact with the flange on the upper ear, so that the hanger supporting member is thus effectively held in two positions, and further wherein the lower crimped arm will hold the garment supporting hangers properly spaced.

To the attainment of the foregoing the invention consists in the improvement herein-after described and definitely claimed.

In the drawings:

Figure 1 is a perspective view of the improvement.

Figure 2 is a detail side elevation thereof.

Figure 3 is a sectional view on the line 3-3 of Figure 2.

Figure 4 is a face view of the wall plate showing the wire supporting hanger swung right angularly thereon.

As disclosed by the drawings the improvement includes a wall plate 1 which is designed to be fixed in a cupboard or on the inner face of a cupboard door or as a matter-of-fact, in any other desired position. The wall plate 1

has its end formed with outstanding ears 2 and 3, respectively. As the wall plate is vertically arranged the ear 3 will be referred to as the upper ear and the ear 2 as the lower ear. The upper ear 3 has its upper edge 55 flanged upwardly, as at 4, and the said flange has its edge centrally formed with a depression 5. It is to be noted that the edges of the flange 4 to the opposite sides of the rounded depression 5 are rounded or arranged at a 60 curvature.

The holding member for the clothes hangers is constructed from a single strand of spring wire bent upon itself to include a lower and substantially horizontal arm 6 65 which is crimped throughout its length and an upper angle arm 7. Both the arms 6 and 7 have their ends bent in the same direction to provide pintles which pass through bearing openings in the ears 2 and 3. The pintle on the upper arm 7 has its end bent angularly, as at 8, to underlie and have frictional contact with the under face of the upper ear 3. The arms 6 and 7 exert a tension toward each other, so that the straight end 9 of the upper arm 7 will, when the device is swung to the position disclosed by Figures 1 and 2 of the drawings, be firmly seated in the notch 5 and likewise when the holder or support is swung right angularly with respect to the wall plate 75 both the arms will exert a pressure against the outer or upper faces of the ears 2 and 3. When in this position the straight end 9 of the arm 7 will be arranged to the rear of the flange 4.

By crimping the lower arm 6 throughout the length thereof the depressions thus afforded serve as seats for the hooked ends of clothes hangers so that such hangers are properly spaced and it is believed that the 80 simplicity of the construction as well as the advantages thereof will be apparent to those skilled in the art to which such invention relates so that further detailed description will not be required.

Having described the invention, I claim:

A garment hanger support comprising a vertical supporting plate having the ends bent and apertured to provide upper and lower ears, a holding member bent upon itself 100

to provide a horizontally disposed arm and an angularly disposed arm and said arms having the ends thereof angularly disposed and positioned through said ears from the 5 upper faces thereof, the angularly disposed end of said angularly disposed arm offset laterally to underlie the lower face of the upper ear, and an upstanding flange on the end of the upper ear and having a depression 10 in its upper edge to receive the angularly disposed arm when in one position, the ends of said flange adapted to act as stops for the angularly disposed arm to engage when the holding member is swung laterally of the 15 supporting plate in either direction.

In testimony whereof I affix my signature.
BROWN NEAL.
